(57) **CLAIM**

The ornamental design for a round arch handle, as shown and described.

DESCRIPTION

FIG. 1 is a front view of a round arch handle showing my design;

FIG. 2 is a right side view thereof;

FIG. 3 is a left side view thereof;

FIG. 4 is a top view thereof;

FIG. 5 is a cross-sectional view taken along line 5-5 of FIG. 4 thereof;

FIG. 6 is a bottom view thereof; and,

FIG. 7 is a perspective view thereof.

The broken lines in the drawings depict environmental subject matter only and form no part of the claimed design.

1 Claim, 7 Drawing Sheets(56)
